United States Patent Office

Des. 187,759

Patented Apr. 26, 1960

187,759

X-RAY VIEWING UNIT

James F. Simmonds, Daleville, and Thomas A. O'Brien,
Indianapolis, Ind.

Application March 19, 1959, Serial No. 55,055

Term of patent 14 years

(Cl. D61—1)

Fig. 1 is a perspective view of an X-ray viewing unit, showing our new design; and

Fig. 2 is a perspective view in viewing position.

A portion of the drawing figures is diagonally lined to indicate transparency.

We claim:

The ornamental design for an X-ray viewing unit, as shown and described.
